UNITED STATES PATENT OFFICE

PHILIP C. P. BOOTY, OF CHICAGO, ILLINOIS, ASSIGNOR TO MICHAEL T. DALEY, OF CHICAGO, ILLINOIS

RECEPTACLE FOR FACE POWDERS

Application filed February 25, 1926. Serial No. 90,474.

My invention relates to receptacles for holding and dispensing face powder and the like in loose form, and particularly to a form of device such as that shown in my prior application Serial No. 10,736, filed February 21, 1925, of which this application is a continuation in part.

It is one of the objects of my invention to provide in a device of this type a new and improved form and arrangement of parts by reason of which the operation of filling the receptacle shall be so easy and so simple that it can be performed readily and quickly by any one who tries whether or not he has any aptitude mechanically. It is another object of my invention to provide a construction of this type so arranged that there shall be under any conditions of use the minimum of likelihood of leakage of the powder at the point where access is had to the interior of the receptacle for filling it. It is still another object of my invention to provide an arrangement by reason of which there shall be the minimum of likelihood of loss of any part of the device when the receptacle is opened for a filling operation.

It is another object of my invention to improve devices of this type in sundry details hereinafter pointed out. The preferred means by which I have accomplished my several objects are illustrated in the drawing and are hereinafter specifically described. That which I desire to cover by Letters Patent is set forth in the claims.

35 In the drawing

Fig. 1 is a perspective view of my improved receptacle, including an outer casing within which the receptacle proper is ordinarily carried.

40 Fig. 2 is a central vertical section through the device of Fig. 1.

Fig. 3 is a fragmentary view similar to a portion of Fig. 2, showing the parts in changed position, and illustrating also a portion of a powder puff in position to receive the powder as it is ejected; and

45 Fig. 4 is a central vertical section through a modified form of receptacle.

Referring first to Figs. 1, 2 and 3, in which corresponding parts are indicated by the same

reference characters,—10 indicates a casing, formed preferably of metal having a lid 11 pivotally mounted therein, the lid preferably being provided with a mirror 12 suitably held in position. Inasmuch as these parts form no part of my present invention, it is believed to be unnecessary to describe them further herein.

The receptacle proper for the face powder comprises a casing 13 formed of sheet metal and provided at its upper end with an integrally formed ring 14 which is tapered downwardly and inwardly. Within the ring 14, there is a second casing member in the form of a ring, also formed of sheet metal, and comprising a tapered portion 15 at its outer face and a more sharply tapered portion 16 at its inner face, the two tapered portions 15 and 16 in the construction shown being integrally united at their upper edges. 60 The shape and proportions of the parts are such that the tapered portion 15 fits snugly within the tapered ring 14 of the casing so as to be held frictionally in tight engagement therewith.

Underlying the lower end of the tapered portion 16, there is a closure plate 17 held yieldingly in position by means of a volute spring 18 which is interposed between the plate 17 and the bottom of the casing 13. The plate 17 is adapted normally to close the opening through the ring comprising the portions 15 and 16, the pressure of the spring being sufficient normally to prevent the escape of powder.

When it is desired to fill the casing 13, the removable ring comprising the portions 15 and 16 is lifted out of engagement with the tapered ring 14, the application of a slight force thereto being sufficient for effecting the removal of the ring. The frictional engagement of the parts is such, however, that under normal conditions the removable ring will not be loosened in use. When a supply of powder has been placed 90 in the casing 13, the parts can be again very quickly and easily replaced so as to make the receptacle again ready for use. When a supply of powder is desired, the plate 17 is moved downwardly, preferably with a 95 100

quick motion, so as to force out a current of air about the periphery of the plate 17, between such plate and the lower end of the tapered portion 16, such current of air serving by pneumatic action to carry out with it a limited supply of the powder. The plate 17 is of slightly larger diameter than that of the ring portion 16, so that there is a projecting shoulder or ledge provided by the plate about the ring portion 16, as is best shown in Fig. 2. The current of air forced outwardly as above described serves to carry out with it the powder which may have become lodged upon the projecting ledge. If, however, there is no such powder on the ledge by reason of a disturbance of the box following the last previous use of the box for dispensing powder, in such case the pneumatic action is such as to force out powder from the body of the casing into position upon the top of the plate 17 or into contact with a powder puff 19 carried on the top face of the plate 17. I have found in practice that by a proper manipulation of the plate 17, the desired amount of powder can be forced out without difficulty.

In Fig. 4 I have shown a modified form of construction which is substantially the same as that above described except for the removable ring. In this construction, the removable ring comprises an outer tapered portion 20 provided with lugs 21 extending inwardly so as to underlie the plate 17, three of such lugs being provided in the construction shown so as to hold the plate 17 in close proximity to the opening through the inner tapered ring portion 22. The ring portions 20 and 22 are also different from the removable ring of the construction shown in Figs. 1, 2 and 3 in that it comprises a rib or shoulder 23 which overlies the upper edge of the casing 13 in slightly spaced relation thereto so that a leverage is provided for forcing the removable ring out of its frictional engagement with the casing 13. By the provision of the lugs 21, the plate 17 is prevented from becoming separated from the removable ring, while at the same time it is permitted to move downwardly to the desired extent for the operation of the device. The spring 18 is also preferably secured to the plate 17, as by means of a suitable quantity of solder 24 so as to prevent the parts from being scattered or separated more than the necessary extent during the operation of filling the receptacle with powder.

Inasmuch as the operation of the device of Fig. 4 is the same as that above described in connection with the device of the other figures, it is believed to be unnecessary to describe the same further.

In the construction shown in Fig. 4, the plate 17 is held at all times against edge-wise displacement from operative closing position with respect to the opening through the

tapered ring portion 22, the play between the edge of the plate and the tapered portion 20 being insufficient to permit such displacement. In the form shown in Figs. 1, 2 and 3, the tapered ring portion 15 holds the plate 17 against displacement edgewise from closing position by a substantially square shoulder engagement therewith until the plate 17 has been lowered to clear such tapered portion 15.

While I prefer to employ the construction as illustrated in my drawing it will be understood that I do not wish to limit my invention to the details of construction as illustrated except to the extent that the same may be specifically claimed.

I claim:

1. A receptacle for face powder and the like, comprising in combination a casing member, a second casing member held by friction in tight engagement therewith, one of said casing members having an opening therethrough independently of the openings at the point where the members are frictionally connected, a plate on the inner face of the casing wall adapted to close said opening and held by engagement with a part of the casing in spaced relation to said opening against displacement edgewise out of operative position with respect to the opening, and spring means adapted normally to hold said plate yieldingly in closing position.

2. A receptacle for face powder and the like, comprising in combination a casing member having an opening therein, a second casing member having a flange fitting said opening and holding said second member frictionally in tight engagement with the first named member, one of said members having a second opening therethrough independently of the openings at the point where the members are frictionally connected, a plate on the inner face of the casing adapted to close said second opening and held by a substantially square shoulder engagement with a part against displacement edgewise out of operative position with respect to the opening, and spring means adapted normally to hold said plate yieldingly in closing position.

3. A receptacle for face powder and the like, comprising in combination a casing member having an opening in its face, a second casing member in the form of a ring having a tapered portion fitting said opening and holding said ring frictionally in tight engagement with the first named member and having a second tapered portion projecting inwardly from said first named tapered portion, a plate on the inner end of said second tapered portion adapted to close the opening therethrough, and a spring adapted normally to hold said plate yieldingly in closing position.

4. A receptacle for face powder and the like, comprising in combination a casing member having an opening in its face, a sec-

5 ond casing member in the form of a ring having a tapered portion fitting said opening and holding said ring frictionally in tight engagement with the first named member and having a second more nearly flat tapered portion 10 projecting inwardly and downwardly from the first named tapered portion, a plate on the inner end of said second tapered portion adapted to close the opening therethrough, and a spring adapted normally to hold said plate yieldingly in closing position.

10 6. A receptacle for face powder and the like, comprising in combination a casing member having an opening in its face, a 15 tapered flange about said opening, a second casing member in the form of a ring having a tapered portion fitting snugly within the tapered portion of the first named casing member and serving to hold the ring frictionally in tight engagement with the first 20 named member and having a third tapered portion projecting inwardly and downwardly from the second tapered portion, a plate on the inner end of said third tapered portion adapted to close the opening therethrough, and a spring adapted normally to hold said plate yieldingly in closing position.

25 7. A receptacle for face powder and the like, comprising in combination a casing member, a second casing member held by friction in tight engagement therewith, means on said second casing member overlying a portion of the first named casing member and slightly spaced therefrom affording leverage for the removal of said second member from the first named member, one of said members having an opening therethrough independently of the openings at the point where the members are frictionally connected, a plate on the inner face of the casing adapted to close the opening and held against displacement edgewise out of operative position with respect to the opening, and spring means adapted normally to hold said 30 plate yieldingly in closing position.

35 8. A receptacle for face powder and the like, comprising in combination a casing member having a circular opening therein, a flange about said opening, a second casing member having a flange fitting within said first named flange for holding said second member frictionally in tight engagement with the first named member, a shoulder on said second casing member overlying a portion of the first named casing member and slightly spaced therefrom affording a leverage for the removal of said second member from the first named member, one of said members having a second opening therethrough independently of the openings at the point where the members are frictionally connected, a plate on the inner face of the casing adapted to close said second opening and held against displacement edgewise out of operative position with respect to the opening, and

spring means adapted normally to hold said plate yieldingly in closing position.

70 9. A receptacle for face powder and the like, comprising in combination a casing member having an opening in its face, a second casing member in the form of a ring having a flange portion fitting said opening and holding said ring frictionally in tight engagement with the first named member, an outwardly extending rib on said ring overlying the first named member in slightly spaced relation thereto affording leverage for the removal of said second member from the first named member, a plate on the inner face of said ring adapted to close the opening therethrough, and a spring adapted normally to hold said plate yieldingly in closing position.

75 10. A receptacle for face powder and the like, comprising in combination a casing member having an opening in its face, a second casing member in the form of a ring having a tapered portion fitting said opening and holding said ring frictionally in tight engagement with the first named member and having a second tapered portion projecting inwardly and downwardly from the upper edge of said first named tapered portion, an outwardly extending rib on said ring overlying the first named member in slightly spaced relation thereto affording leverage for the removal of the ring from the first named member, a plate on the inner face of said ring adapted to close the opening therethrough, and a spring adapted normally to hold said plate yieldingly in closing position.

80 11. A receptacle for face powder and the like, comprising in combination a casing member having an opening in its face, a tapered flange about said opening, a second casing member in the form of a ring having a tapered portion fitting snugly within the tapered portion of the first named member and serving to hold the ring frictionally in tight engagement with the first named member, an outwardly extending rib on said ring overlying the upper edge portion of said flange in slightly spaced relation thereto affording leverage for the removal of the ring from the first named member, a plate on the inner face of said ring adapted to close the opening therethrough, and a spring adapted normally to hold said plate yieldingly in closing position.

85 12. A receptacle for face powder and the like, comprising in combination a casing having an opening in one face and having an in-turned flange about said opening, a plate on the inner end of said flange adapted to close the opening therethrough, and inwardly projecting lugs carried by said casing and underlying said plate for holding the plate in close proximity to said flange.

90 13. A receptacle for face powder and the like, comprising in combination a casing hav-

ing an opening thereinto, a plate on the inner face of said casing adapted to close the opening, a spring adapted normally to hold said plate yieldingly in closing position, and other 5 means for holding said plate in close proximity to said opening.

13. A receptacle for face powder and the like, comprising in combination a casing member having an opening in its face, a second 10 casing member in the form of a ring removably mounted in tight engagement with the first named member, a plate on the inner face of said ring adapted to close the opening therethrough, a spring adapted normally to hold said plate yieldingly in closing 15 position, and means carried by said ring for holding said plate in close proximity to said opening.

14. A receptacle for face powder and the like, comprising in combination a casing member, a second casing member held by friction in tight engagement therewith, one of said casing members having an opening therethrough independently of the openings 25 at the point where the members are frictionally connected, a plate on the inner face of the casing adapted to close the opening and held against displacement edgewise out of operative position with respect to the opening, and spring means adapted normally to hold said plate yieldingly in closing position, the arrangement being such that by the inward and outward movements of the plate air is forced from the casing through said opening for carrying a supply of powder from the receptacle.

15. A receptacle for face powder and the like, comprising in combination a casing member having an opening therein, a second 40 casing member having a tapered flange fitting said opening and holding said second member frictionally in tight engagement with the first named member, one of said members having a second opening therethrough independently of the openings at the point where the members are frictionally connected, a plate on the inner face of the casing adapted to close said second opening and held against displacement edgewise out 45 of operative position with respect to the opening, and spring means adapted normally to hold said plate yieldingly in closing position, the arrangement being such that by the inward and outward movements of the plate air is forced from the casing through said second opening for carrying a supply of powder from the receptacle.

16. A receptacle for face powder and the like, comprising in combination a casing 60 member having an opening in its face, a second casing member in the form of a ring having a flange portion fitting said opening and holding said ring frictionally in tight engagement with the first named member, a plate on the inner face of said ring adapted

to close the opening therethrough and having its edge in spaced relation to said opening, and a spring adapted normally to hold said plate yieldingly in closing position, the arrangement being such that by the inward and outward movements of the plate air is forced from the casing through the opening in the ring for carrying a supply of powder from the receptacle. 70

17. A receptacle for face powder and the like, comprising in combination a casing member having an opening in its face, a tapered flange about said opening, a second casing member in the form of a ring having a tapered portion fitting snugly within the tapered portion of the first named casing member and serving to hold the ring frictionally in tight engagement with the first named member, a plate on the inner end of said second tapered portion adapted to close the opening therethrough, and a spring adapted normally to hold said plate yieldingly in closing position, the arrangement being such that by the inward and outward movements of the plate air is forced from the casing through the opening in the ring for carrying a supply of powder from the receptacle. 75

18. A receptacle for face powder and the like, comprising in combination a casing member, a second casing member held by friction in tight engagement therewith, means on said second casing member overlying a portion of the first named casing member and slightly spaced therefrom affording leverage 100 for the removal of said second member from the first named member, one of said members having an opening therethrough independently of the openings at the point where the members are frictionally connected, a plate on the inner face of the casing adapted to close the opening and held against displacement out of operative position with respect to the opening, and spring means adapted normally to hold said plate yieldingly in closing position, the arrangement being such that by the inward and outward movements of the plate air is forced from the casing through said opening for carrying a supply of powder from the receptacle. 105

19. A receptacle for face powder and the like, comprising in combination a casing member having an opening in its face, a second casing member in the form of a ring having a tapered portion fitting said opening and holding said ring frictionally in tight engagement with the first named member and having a second tapered portion projecting inwardly and downwardly from the upper edge of said first named tapered portion, an 120 outwardly extending rib on said ring overlying the first named member in slightly spaced relation thereto affording leverage for the removal of the ring from the first named member, a plate on the inner face of said ring 125 130

adapted to close the opening therethrough, and a spring adapted normally to hold said plate yieldingly in closing position, the arrangement being such that by the inward and downward movements of the plate air is forced from the casing through said second opening for carrying a supply of powder from the receptacle.

20. A receptacle for face powder and the like, comprising in combination a casing having an opening in one face and having an inturned flange about said opening, a plate on the inner end of said flange adapted to close the opening therethrough, a spring adapted normally to hold said plate yieldingly in closing position, and other means for holding said plate in close proximity to said flange, the arrangement being such that by the inward and outward movements of the plate air is forced from the casing through said opening for carrying a supply of powder from the receptacle.

21. A receptacle of the class described comprising a casing having a tapered seat, a member adapted to fit snugly in said seat and having an inwardly extending perimetrical flange, cover means for the casing and underlying said flange, and yieldable means for normally holding said cover means against said flange.

22. A receptacle of the class described comprising a casing having a tapered seat, a member adapted to fit snugly in said seat and having an inwardly extending perimetrical flange, cover means for the casing and underlying said flange, and a volute spring interposed between the bottom of said casing and the under side of said cover means for normally holding said cover means against said flange.

23. A receptacle for face powder and the like, comprising in combination a casing member having an opening in its top face, a second casing member removably secured in said opening, said second casing member having an opening therethrough, a plate underlying the opening in said second casing member and having its outer edge in spaced relation to said opening, and spring means adapted normally to hold said plate yieldingly in position for closing said second opening.

24. A receptacle for face powder and the like, comprising in combination a casing member having an opening in its top face, a second casing member removably secured in said opening and having a portion tapered inwardly and downwardly to an opening therethrough, a plate underlying the opening in said second member with its marginal portion in convergent position with respect to said tapered portion of the second casing member, and spring means adapted normally to hold said plate yieldingly in position for closing said second opening.

25. A receptacle for face powder and the

like, comprising in combination a casing member having an opening in its top face, a second casing member removably secured in said opening, said second casing member having an opening therethrough, a plate underlying the opening in said second casing member with its outer edge spaced substantially from said opening and held by engagement with a part of the casing against edgewise displacement laterally with respect to said second opening, and spring means adapted normally to hold said plate yieldingly in position for closing said second opening.

26. A receptacle for face powder and the like, comprising in combination a casing member having an opening in its top face, a second casing member removably secured in said opening, said second casing member having an opening therethrough, a plate underlying the opening in said second casing member, spring means adapted normally to hold said plate yieldingly in position for closing said second opening, and means adapted normally for holding the plate and the spring attached to the casing when the casing members are detached from each other.

27. A receptacle for face powder and the like, comprising in combination a casing member having an opening in its top face, a second casing member removably secured in said opening, said second casing member having an opening therethrough, a plate underlying the opening in said second casing member, spring means adapted normally to hold said plate yieldingly in position for closing said second opening, and means adapted normally for holding the plate attached to said second casing member so as to enable them to be removed as a unit from the first named casing member.

28. A receptacle for face powder and the like, comprising in combination a casing member having an opening in its top face, a second casing member removably secured in said opening, said second casing member having an opening therethrough, a plate underlying the opening in said second casing member, spring means adapted normally to hold said plate yieldingly in position for closing said second opening, and means adapted by cooperation with the remaining parts under normal conditions of use to hold the second casing member, the plate and the spring means together as a unit when removed from said first named casing member.
